TELETYPEWRITER

Otto Moser, Bern, Switzerland

Application August 18, 1954, Serial No. 450,699

Claims priority, application Switzerland
November 25, 1953

2 Claims. (Cl. 178—23)

My invention relates to teletypewriters and similar teleprinting apparatus that are selectively operable as a transmitter as well as a receiver and that operate to type the message, being transmitted or received, onto a sheet passing about a platen roller. During transmitting operation, the text being typed serves to provide one or several confirmation copies. The typing in such apparatus is effected by means of type faces acting upon an inking ribbon in much the same manner as in an ordinary typewriter.

For distinguishing the incoming and outgoing messages, the known teletypewriters are provided with two-color printers which produce the text in a selected color indicative of the direction of communication. For instance, incoming messages are typed in black while outgoing messages appear in red. A salient disadvantage of such apparatus lies in the fact that the distinction between incoming and outgoing messages appears only on the first sheet but not on any carbon copies.

According to another proposal that does not incur this disadvantage and upon which the present invention is predicated, a teleprinter is provided with a marking device that adds to the text a typed character distinguished incoming from outgoing messages. This marking device is actuated by means incorporated in the printing mechanism and operating under control by devices that are effective only during operation of the machine in one of the two directions of communication.

According to the just-mentioned proposal, an intermediate member is longitudinally displaced prior to the printing operation proper so that the displacement causes a marking type-face mounted on the intermediate member to reach a position in front of the inking ribbon. The displacement is caused by a cam disc that revolves only when the teleprinter operates in one given direction of traffic. When the type face and the paper to be imprinted occupy the proper relative positions, the intermediate member is struck by a pivotally mounted striker so that the type face imprints an identifying character upon the paper. The control of the intermediate member in this apparatus is entirely mechanical.

It is an object of my invention to provide a teleprinter with a marking device for the above-mentioned purpose that is distinguished from the known marking devices by a simplified and space-saving design of improved reliability. To this end, and in accordance with a feature of my invention, I provide the marking device with a type-carrying rod or plunger equipped with coupling means that enter into the operating range of actuating devices under control by an electromagnet; and I control the energizing circuit of the electromagnet by a contact actuated by the rotation of a cam disc occurring only when the machine operates in a given direction of traffic.

The foregoing and other objects and features of the invention will be apparent from the embodiments exemplified by the drawings and described in the following. In the drawings:

Fig. 1 shows a lateral view of a marking device ac-

2

cording to the invention, Fig. 2 is a partial top view of the same device; Fig. 3 is a partly sectional top view of the receiving portion of a teleprinter equipped with a marking device according to Figs. 1 and 2, the housing of the apparatus being removed, and Fig. 4 is a rear view of the device according to Figs. 1 and 2.

The illustrated teleprinters have a platen roller for accommodating a sheet to be typed upon and are provided with a printing device. During the operation of the machine, the platen roller moves back and forth along the printing device in the direction of the lines of characters to be typed. The printing device has a type carrier in the form of a group of coaxial type wheels each comprising a peripherally distributed group of type faces. The cylindrical type carrier is revolvably mounted on a swingable support, and the selection of the particular type face to be imprinted at a time is effected by revolving the type carrier in accordance with pulse combinations being received or transmitted.

Teleprinting apparatus of this kind are known as such, an example of improved design is described and illustrated in detail in my copending application Serial No. 412,513, filed February 25, 1954, entitled Teletypewriter. However, the following description, relating to Fig. 3 of the drawing, goes beyond the marking device of my invention proper and includes as many of the associated teleprinter components as have to be mentioned for conveying a complete understanding of the invention although, if desired, reference may also be had to my copending application mentioned above.

Now, according to the present invention, the teleprinter generally described above, is provided with a marking device responsive to the direction of traffic. The marking device comprises a cam shaft 1 (Fig. 1) that revolves only when the teleprinter is operating in the one traffic direction for which the text being typed is to be marked. For instance, the cam shaft 1 may constitute the transmitter control shaft if the outgoing messages are to be provided by a distinctive mark. Mounted on shaft 1 is a cam disc 2 coating with an electric contact 3. When the cam shaft 1 is in the illustrated position of rest, the contact 3 is open. When the cam shaft 1 revolves, the contact 3 is closed during substantially the entire period of revolution. Contact 3 is connected in an excitation circuit which includes a current source 19, an electromagnet 34 and another contact 17. The contact 17 is a limit contact and is closed only when the platen roller 21 (Fig. 3) is in one of its two end positions of travel, for instance at the beginning of a line to be typed.

The teleprinter shown in Fig. 3 has a frame structure 147 with a stationary guide rail 144 along which a carriage 149 is displaceable. Revolvably mounted on the carriage are the platen roller 21 and a supply roller 148 from which a sheet of paper passes around the platen roller. The receiver-printer assembly 141 of the teleprinter is stationarily mounted on the frame structure and has a type carrier 143 controlled and actuated to type upon the paper in the manner described above. After each individual typing operation, the platen with carriage shifts one step toward the left until it reaches the end-of-line position shown in Fig. 3. The platen roller is actuated by a line-shift device. This device comprises a double-armed lever 22 freely revolvable on the shaft 23 of the platen roller. One arm 22a of lever 22 is connected with the line-shift drive (not shown) controlled by the pulse-responsive receiver of the teleprinter. The other arm 22b of lever 22 carries a pivotally movable pawl 24 engaging a ratchet gear 25 that is firmly mounted on the platen roller shaft 23. To prevent obscuring of other parts, the ratchet gear 25, fully shown in Figs. 2 and 3, is shown in Fig. 1 only by dot-

and-dash lines. In Figs. 1 and 2, the parts of the marking and line-shifting devices are shown in the active position by heavy lines and in the position of rest by thin lines.

The marking device has a marking plunger 26 mounted on a carrier 29 that is pivoted by a pin 28 to a bracket 27 firmly attached to the carriage structure 149. The marking plunger 26 is actuated by the line-shift device through a coupling lever 30. Lever 30 is linked by a pivot pin 31 to the carrier 29. A coupling pin 32 is fixed to a projection 30a (Fig. 7) of lever 30 to cooperate with a cam portion 22c of the lever 22 of the line-shift device. Lever 30 is kept in the position of rest by the force of a spring 33. In this position, the coupling pin 32 is outside of the active range of cam portion 22c. An electromagnet 34 serves to control the coupling lever 30.

The armature 35 of electromagnet 34 is pivotally mounted on a pin 36 and has an extension 35a. When the armature is attracted, the extension 35a presses the coupling lever 30 against a stop 37. This moves the coupling pin 32 into the active range of cam portion 22c. Assuming that the teleprinter is so set that the marking device will operate and produce an identifying mark on the confirmation copy when the machine operates as a transmitter, the above-described marking device operates as follows:

By depressing the line shift key of the transmitting teleprinter, the transmitter control shaft 1 is released to perform one single full revolution. The cam-controlled contact 3 closes as soon as the transmitter control shaft 1 leaves its initial position. In this manner, the energizing circuit of electromagnet 34 is completed. The armature 35 is attracted so that, as described, the marking device is coupled with the line-shift mechanism. At the same time, the pulse-responsive receiver in the same teleprinter is placed in operation and receives the code-pulse combination "line shift" which controls the line-shift mechanism to perform the line shift command. During line shifting, the lever 22, and together therewith the platen roller 21, are turned one step by the pawl 24 acting upon the ratchet 25 in the counterclockwise direction (Fig. 4). At the same time, the coupling pin 32 of lever 30 is lifted by its engagement with the cam portion 22c of lever 22 and moves the coupling lever 30 in such a manner (toward the left in Figs. 1 and 2) that the carrier with the marking plunger 26 is swung against the platen roller 21, thus producing an imprint of the marking character.

Such an automatically-operating device for the discriminating marking of teleprinter messages is particularly advantageous for use with teleprinters exclusively or selectively controllable by means of punched strips.

It will be obvious to those skilled in the art, upon a study of this disclosure, that my invention permits of various modification as regard the details of the marking device and its arrangement on the teleprinter, and hence can be given embodiments other than those specifically described and illustrated, without departing from the essential features of my invention and within the scope of the claims annexed hereto.

I claim:

1. In combination, a page-printing teleprinter for communication in both directions comprising a stationarily journaled platen roller and a revolvable shaft carrying said roller, said teleprinter having a line-shift mechanism connected with said shaft for imparting stepwise revolution to said platen roller, a marking device for imprinting an identifying character indicative to the direction of communication, said marking device being stationarily mounted at one end of the platen roller and having a type carrier member, said carrier member being movable in a direction toward said platen roller for imprinting said character, a cam mounted on said shaft, a coupling lever connected to said carrier member and operative to move said carrier member in the character imprinting direction, said coupling member being normally disengaged from said cam, an electromagnet having a movable armature, means controlled by movement of said armature to move said coupling lever into the operating range of said cam when said magnet is energized, said cam being operative to control said coupling lever for operating said carrier during line-shift operation of said mechanism, and an electric energizing circuit connected with said magnet and comprising circuit-control means responsive to teleprinter operation in a given one of said directions of communication for energizing said magnet.

2. In combination, a page-printing teleprinter for communication in both directions comprising a carriage displaceable in the printing-line direction, a roller shaft revolvably mounted on said carriage parallel to said direction, a platen roller on said shaft, a line shift mechanism connected with said shaft for imparting stepwise revolution to said platen roller, a marking device for imprinting an identifying character indicative to the direction of communication, said marking device being mounted on said carriage to travel together therewith and having a type carrier near one end of said platen roller, said carrier being normally spaced radially from said roller and being movable toward said roller, a cam mounted on said shaft, a coupling member linked to said carrier for moving it in imprinting direction, said coupling member being normally disengaged from said cam, an electromagnet having a movable armature, means controlled by movement of said armature to move said coupling member into the operating range of said cam when said magnet is energized, said cam being operative to control said coupling member for operating said carrier during line-shift operation of said mechanism, and an electric energizing circuit connected with said magnet and comprising circuit-control means responsive to teleprinter operation in a given one of said directions of communication for energizing said magnet.
